UNITED STATES PATENT OFFICE.

DORA MORNER, OF STEVENS POINT, WISCONSIN.

SANITARY BELT.

1,423,353.

Specification of Letters Patent. Patented July 18, 1922.

Application filed October 31, 1921. Serial No. 511,551.

To all whom it may concern:

Be it known that I, DORA MORNER, a citizen of the United States, and resident of Stevens Point, in the county of Portage and State of Wisconsin, have invented certain new and useful Improvements in Sanitary Belts; and I do hereby declare that the following is a full, clear, and exact description thereof.

10 My invention relates to a new and useful improvement in sanitary belts such as are provided with means for supporting the ends of a napkin during the period of menstruation.

15 The object of the invention is especially to provide improved means for holding the clamp which supports the end of the napkin so that there is no chance of its becoming accidentally detached.

20 In describing my invention reference will be made to the accompanying drawings, in which:—

Figure 1 is a perspective view of my invention, and

25 Figure 2 is a detail view of the clamp.

Referring more particularly to the drawing, the belt comprises two portions 5 and 6 to which are connected the flexible supporting members 7 and 8. Each of these supporting members has a pair of eyes 9 in which a clamp 10 is secured which supports the end of the napkin 11.

30 The clamp comprises a rectangular loop 12 formed from comparatively stiff wire and having the inturned ends 13 and 14. A sleeve 15 is suitably secured to one of the inturned ends, as for example 13 and the other end of the sleeve receives the other inturned end which is provided with a laterally extending tip 16 which normally registers with a recess in the sleeve. A second loop 17 is substantially the same shape as the first described loop but slightly smaller and is provided at its ends with eyes 18 which

45 pivotally receive the inwardly projecting ends 13 and 14. The wire from which the loop 12 is formed is sufficiently resilient to permit the end 14 to be separated from the sleeve so that the latter may be inserted

50 through the eyes 9. The end of the napkin

is clamped in the usual manner and when the sleeve has been inserted through the eyes 9 and the tip 16 inserted in the recess of the sleeve as shown in Figure 2 the napkin is securely clamped and there is no possibility 55 of the clamp becoming separated accidentally from the supporting member 7 or 8.

While I have shown and described one specific form in which my invention may be embodied it will be understood that the invention includes all equivalents which may fall within the scope of what is claimed.

I claim as my invention:—

1. In a device of the character described, a clamp comprising a substantially rectangular loop, one side of the rectangle being formed by the ends of the loop extending toward each other and a sleeve secured to one of the ends and separably receiving the other end, and a second loop of approximately the same shape but slightly smaller than the first loop and having eyes formed in its ends and pivotally receiving the ends of the first loop.

2. In a device of the character described, 75 a clamp formed from two members each comprising a substantially rectangular loop of comparatively stiff wire, one side of one rectangle being formed by the ends of the loop extending toward each other and 80 a sleeve secured to one of the inwardly turned ends and detachably receiving the other end, said last named end terminating in a laterally projecting tip, a recess in the sleeve receiving said tip to yieldingly hold 85 the loop in closed position, the other loop being slightly smaller than the first described loop and having eyes formed in its ends and pivotally receiving the inwardly turned ends of the first described loop, and 90 a support having attaching eyes which may be slipped over the end of said sleeve when the detachable loop end is removed therefrom.

In testimony that I claim the foregoing 95 I have hereunto set my hand at Stevens Point, in the county of Portage and the State of Wisconsin.

DORA MORNER.
